UNITED STATES PATENT OFFICE.

LELAND S. HAMER, OF FULLERTON, CALIFORNIA, ASSIGNOR OF ONE-HALF TO WILLIAM WEBSTER WILSON, OF LOS ANGELES, CALIFORNIA.

PIPE-HOOK TONGS.

Application filed April 21, 1921. Serial No. 463,423.

To all whom it may concern:

Be it known that I, LELAND S. HAMER, a citizen of the United States, residing at Fullerton, in the county of Orange and State of California, have invented new and useful Improvements in Pipe-Hook Tongs, and the following is such a full, clear, and exact disclosure of the invention that anyone skilled in the art to which it appertains may 5 make and use the same.

This invention relates generally to pipe tools, and specifically to a tool comprising a hook and tong arrangement for handling pipe.

10 While the herein disclosed invention may be found useful in many fields, and in connection with various classes of work, the device was primarily conceived and designed for use in connection with well drilling operations; and therefore its principles of construction and operation will be explained in connection with such work, although it is to be understood as not limited to such.

In the drilling and operation of oil wells 15 it is frequently necessary to pull the casing or pipe from the bore, for various reasons; this being done by means of a cable passing over a sheave at the top of the derrick, one end of which is secured to a winding drum 20 while the opposite end carries an adjustable device, termed the "elevator," which is adapted to be removably secured to the top end of the pipe section being pulled. The pipe or casing is ordinarily pulled and disconnected in eighty foot lengths or stands, 25 and stood on end on the derrick floor, in position to be again put in the bore. A piece of timber, termed the "finger" is mounted upon one of the derrick girts, adjacent the 30 top of the derrick, and extends inwardly at an angle with this girt across one corner of the structure, and back of which the top ends of the pipe sections or stands are placed to hold them in standing position in this 35 corner of the derrick structure. During the pulling operation a workman stands on the derrick structure, near its top, to guide and bring the pipe stands back of the finger and to release the elevator therefrom preparatory 40 to its being lowered for attachment to another section.

The type of elevator most commonly used 45 comprises a collar portion having a hinged section on one side, by means of which it is removably secured about the pipe, below one

of the pipe collars. Bails, pivotally attached to this collar, extend upwardly from opposite sides thereof, and the cable is passed through these bails and secured upon itself. After the pipe drawn from the bore has been 50 moved into position and stood upon the derrick floor, the lifting cable is slackened and the elevator slides down the pipe a short distance, where it is removed by the workman above referred to. If in setting the 55 pipe it is turned so a slackening of the lifting cable will permit the bails to fall on the same side of the pipe as the opening section of the collar, the elevator cannot be removed without again drawing it to the top of the 60 pipe. Therefore, before resting upon the derrick floor the pipe must be so turned that the elevator bails will fall upon the side opposite the collar opening; and, as these 65 pipes are generally covered with oil it is very difficult for the workman stationed upon the derrick to grip the pipe with one hand to turn it, especially as he must hold on to the derrick with the other hand while 70 performing this work. Furthermore, it is 75 not practicable to attempt to perform this function from the derrick floor.

Having in mind the aforementioned difficulties, I have provided a tool, adapted to be 80 operated with one hand while the workman is holding on to the derrick with the other, whereby he may easily and conveniently 85 grip the pipe to bring it to proper position back of the finger, and also to axially rotate it in either direction, while suspended, to 90 bring the elevator into proper position for release.

My invention is characterized by (1) a 95 tool which is simple, durable and inexpensive to manufacture; (2) which is arranged to be easily and quickly attached to and detached from the pipe; and (3) which may be operated by one hand.

The details of construction and operation 100 of my device will be more fully set forth in the following specification, reference being made therein to the accompanying drawings, forming part thereof, and in which:

Fig. 1 is a plan view of the device showing it adjusted to a pipe section and in gripping position to rotate the pipe in one direction; Fig. 2 is a view similar to Fig. 1 only showing the device in position to grip the pipe and turn it in another direction; Fig. 3 105 is a fragmentary view similar to Figs. 1 and 110

2, parts being shown in section; Fig. 4 is a front view of the device; and Fig. 5 is a rear view thereof.

Referring now to the drawings the device 5 comprises essentially a relatively stationary handle member 10 on which a relatively movable pipe embracing member 11 is pivotally mounted. The member 10 is preferably constructed of flat metal, and preferably 10 bent to the configuration shown to form a handle 12, and terminating in a pair of parallel spaced portions 13; although any other type of construction which will accomplish my purpose may be used. In plan the portion 10 may be curved as shown, or if preferred it may be straight or even curved 15 slightly in the opposite direction.

The portion 11 is preferably constructed of flat metal and of the configuration 20 shown, being substantially circular, and of a length to extend around the pipe 14 slightly more than half way. The free end 25 of the member 11, is provided with teeth 16 on its inner edge, which teeth are adapted to engage the periphery of the 30 pipe 14; and in order that they will cooperate with other elements of the device in turning the pipe in either direction, these teeth are preferably formed to extend radial of the periphery of the pipe when in contact therewith.

The member 11 is pivotally secured to the member 10, by means of a bolt or pin 35 17, the portion 11 extending in a plane between and parallel with the portions 13 of the member 10, and the bolt 17 passing through registering apertures in all three members.

An extension 18 is formed on the pivotal 40 end 19 of the member 11; this portion having an arcuate slot 20 concentric with the pivot pin 17, through which a bolt 21—carried by lugs 22 formed on the members 13—extends. The function of this bolt is 45 to limit the pivotal movement of the portion 11 relative to the portion 10.

Teeth 23 and 24 are cut in the inner edges of the parallel members 13, on either 50 side of the pivot pin 17; these teeth being adapted to alternately engage the periphery 55 of the pipe 14, in cooperation with the teeth 16, when the portion 10 is moved to the right or left to rotate the pipe. It will be noted that the teeth 23 extend in one direction while the teeth 24 extend in the opposite direction; the reason for this being that when it is desired to turn the pipe in the direction indicated by the arrow in Fig. 1, the handle 10 is moved in the direction indicated by the arrow thereon and the teeth 24 brought into engagement with the periphery of the pipe 14; this movement clamping the member 11 about the pipe and likewise bringing the teeth 16 into engagement with its periphery. Continued move-

ment of the handle 10 in the direction indicated will rotate the pipe. When it is desired to rotate the pipe in the opposite direction as indicated by the arrow in Fig. 2, the handle 10 is moved in the direction indicated by the arrow thereon, and the teeth 23 similarly brought into engagement with its periphery; which, in conjunction with the teeth 16, will grip the pipe sufficiently to cause this rotation on continued movement of the handle 10 in the direction indicated.

Preferably the portion 11 is formed in a substantial portion of a circle only slightly larger than the diameter of the pipe 14, to obviate unnecessary play and relative movement between the members; and it is desired that the teeth 16 extend beyond the plane of the inner edge of the portion 11 so as to form a positive engagement with the pipe, as is also the case with the teeth 23 and 24.

While in all cases it may not be necessary, it is preferred that the arcuate length of the portion 11 between the teeth 16 and the pivotal point 17 be sufficient to extend slightly more than half way around the pipe 14, so that when the parts are moved to the position shown in Fig. 2, to turn the pipe in the direction indicated, the teeth 23 will be substantially diametrically opposite the teeth 16, thereby insuring a positive clamping engagement with the pipe.

Thus it will be seen that I have produced a tool which, in operation, may be held in one hand of a workman, to engage a suspended pipe section—normally out of his reach—by the portion 11 to draw or swing it into standing position, back of the finger, at the same time moving the handle portion 10 to the right or left to rotate the pipe to bring the elevator into proper position for releasement.

While I have shown and described the preferred embodiment of my invention, it is nevertheless to be understood that I reserve the right to make any changes of modifications in structure which properly come within the scope of the appended claims.

Having described my invention, I claim:

1. In a device of the character described, a handle; a pipe embracing member pivotally mounted adjacent one end upon the handle; pipe engaging teeth upon said handle on each side of said pivot; and means on said embracing member cooperating with means on the handle to limit their relative movement in either direction.

2. In a device of the character described, a handle; an arcuate pipe embracing member pivotally mounted adjacent one end upon the handle; pipe engaging teeth upon said handle on each side of said pivot; a

- pin in one of said members; an arcuate slot in the other of said members, concentric with said pivot, engaged by said pin to limit relative movement between the two.
- 5 3. In a device of the character described, a pipe embracing member somewhat more than semicircular in extent having pipe engaging teeth at one end, a pivot near the other end of said member located somewhat
- 10 more than half a circumference from said teeth; a handle member pivoted on said pivot, extending on both sides of the pivot in a direction generally the same as the circumferential extent of the pipe embrac-
- 15 ing member at the pivot, and having teeth on its inner edge that face the teeth on the other end of the pipe embracing member, said teeth on said edge being located near the end of the handle member at one side of the pivot and also on said edge at the 20 other side of the pivot, all of said teeth being removed from the teeth on the pipe embracing member by a distance substantially not less than half a circumference.

In witness that I claim the foregoing I 25 have hereunto subscribed my name this 9th day of March, 1921.

LELAND S. HAMER.

Witness:

VIRGINIA BERNER.
